UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

49,848.

Specification for Design.

Patented Nov. 7, 1916.

Application filed August 30, 1916. Serial No. 117,809. Term of patent 3½ years.

To all whom it may concern:

Be it known that I, JOHN S. MONAGHAN, a citizen of the United States, and a resident of the city of Rochester, county of Monroe, and State of New York, have invented a new, original, and ornamental Design for Buttons, of which the following is a specification.

My design is represented in the accompanying drawing, in which;

Figure 1 is a plan view of a button showing my new design. Fig. 2 is an end elevation.

The button is provided with four sides, each side of which is curved. The upper surface of the button at the edges is beveled and smooth, and just inside of the bevels is a circular portion which is roughened. A central projection is provided which is flat on top, the sides of which are circular, the

upper edges of which are beveled so as to form a central flat portion which has a contour, the outer border of which is substantially the shape of the button. The central portion is mottled and the outer edge of the upper face is in solid color. The bottom of the button is smooth and is formed with a central projection as shown.

I claim:

The ornamental design for a button substantially as shown and described.

In witness whereof I have hereunto set my hand at Rochester, in the county of Monroe and State of New York, this 25th day of August, 1916.

JOHN S. MONAGHAN.

In presence of—

N. D. HULBURT,
EARL A. WELLER.
